(57) **CLAIM**

The ornamental design for a storage box, as shown and described.

DESCRIPTION

FIG. 1 is a perspective view of a storage box comprising the new design;

FIG. 2 is a top view thereof;

FIG. 3 is a front elevational view thereof, where the rear elevational view is a mirror image thereof;

FIG. 4 is a right side elevational view thereof, where the left side elevational view is a mirror image thereof;

FIG. 5 is a perspective view of an alternate embodiment of a storage box, portions of which are cut away to illustrate indeterminate length, which is the sole difference between it and FIGS. 1 through 4;

FIG. 6 is a perspective view of the claimed design, shown in an alternate position of use where outer lids of the claimed design are shown partially opened;

FIG. 7 is a perspective view of the claimed design, shown in an alternate position of use where outer lids of the claimed design are shown opened to a horizontal position; and,

FIG. 8 is a perspective view of the claimed design, shown in an alternate position of use where outer lids of the claimed design are shown opened to a downwardly-directed vertical position and a center lid is separated.

The broken lines are for illustrative purposes and form no part of the claimed design.
